COMBINATION LAMP AND FAN UNIT

Alexander E. Blumenthal, Pittsburgh, Pa.

Application April 14, 1938, Serial No. 201,865

14 Claims. (Cl. 230—249.5)

My invention relates to a combination lamp and fan unit for the purpose of air circulation, conditioning, and illumination. Heretofore, attempts to create such a unit have not been successful insofar as I am aware. Previous constructions have not received public approval for the reason that the unit was not sufficiently artistic for internal use; or where some semblance of pleasing appearance was obtained, it was at the expense of the operating characteristics and silence of the fan, or at the expense of the efficiency of the lamp as a source of illumination, or both.

It is accordingly a general object of my invention to create a combination lamp and fan of attractive appearance.

It is a further object of my invention to create a combination lamp and fan unit capable of performing its function as a fan silently and effectively as well as capable of performing its function as a source of illumination efficiently.

In achieving the above and other objects of my invention, I provide deflectors which guide the intake and outlet air to and from the unit along proper flow streams or paths. The shape and points of termination of the deflectors conform to an artistic and attractive design so as to make a pleasing impression. Moreover, the deflectors shield the working parts of the fan, that is the motor and fan blades, from view, and one of the air deflectors is utilized also as a reflector for the illuminating means of the unit, thereby performing two functions. In addition, I cause a small amount of light from the illuminating means to fall directly and indirectly upon the visible surfaces of a majority of the deflectors. These surfaces may be painted with pastel shades or otherwise treated so that when the indirect light falls upon them an engaging light effect of enhanced value is obtained.

It is accordingly a more or less specific object of my invention to produce a fan having a plurality of spaced deflectors arranged in an attractive manner, and which completely hide the moving and power fan parts from view.

A further innovation by my invention is the utilization of a single member for guiding the flow of air and at the same time acting to reflect light from the illuminating means in the unit in a desired direction or directions.

Many other objects, innovations, and novel features of my invention will be apparent from the following description thereof, taken in conjunction with the drawings, in which:

Fig. 1 is an elevational view of one embodiment of my invention.

Fig. 2 is an exploded sectional perspective view of a part thereof.

Fig. 3 shows a modified supporting element of my unit.

Fig. 4 shows a modified head portion of my combination unit.

Fig. 5 shows an embodiment for a hanging unit employing the principles of my invention.

Fig. 6 shows an exploded construction of a bracket spider that can be employed as a supporting structure.

Referring to the embodiment shown in Figs. 1 and 2, the combination unit comprises a downwardly dished base 10, supported upon legs 11. In a conventional manner three stem rods 12, arranged at the corners of an equilateral triangle, are clamped between the base 10 and a housing 13. The housing 13 comprises a cast, pressed, spun or otherwise formed cup-like member having an annular base 14 integral with an upstanding slightly tapered tube 15 which has its smaller diameter towards the rods 12. I employ this form of housing because I obtain symmetry in the head unit indicated in its entirety by the numeral 16.

Secured or fastened in any suitable manner along the inner periphery of the annular base 14 and extending downwardly therefrom between the rods 12 is a small cup 17 for a purpose to be hereinafter described. Iron pipes (not shown) of a diameter small enough to pass through the rods 12, and of a length somewhat greater, are within the rods 12.

As is common in the art, these pipes are threaded at both ends. The lower ends may be screwed into tapped holes in the base 10 if the latter is sufficiently thick for the purpose. If not, the pipes may have nuts or the equivalent at the bottom end abutting the underside of the base in accordance with usual practice. The upper ends of the pipes have nuts 18 screwed thereon which serve to clamp the rods 12 between the base 10 and the housing 13, thereby creating a rigid pedestal structure indicated in its entirety by the reference numeral 19. If the pipes screw into tapped holes in the base, the nuts 18 are the tightening means by which the rods 12 are clamped as aforesaid. If the pipes have nuts on the bottom ends thereof then these nuts or the nuts 18 may be the tightening means.

A cup 20 is the unit about which the elements of head 16 are supported. This cup has a taper corresponding generally to that of the housing 13 so that the head may be assembled on the pedestal by inserting the cup 20 into the housing, the tapering of the parts resulting in a snug mating fit ample to give a solid assembly. While any appropriate type of fit, detachable or not may be employed, I prefer the taper fit since this fit has no protruding parts to mar the appearance of the unit and is easily manipulated. By making the head and pedestal detachable I can interchange different pedestals with different head units and so provide a wide range of lamp selections with a minimum stock of head and pedestal

units. Moreover, because the pedestal and head unit are easily assembled and dismantled, transportation of the unit is facilitated. This is of particular merit, and a decided advantage in such businesses as the undertaker's profession in which paraphernalia must be moved from place to place.

The fan comprises a motor 21 suspended vertically within cup 20 with an air space between the motor frame and the cup as shown more clearly in Figs. 2 and 4. The fan also comprises a four blade silent propeller 22 secured to the vertical shaft 23 of the motor, although any other propeller of the silent type may be substituted. The propeller propels air upward in the structures shown. The fan of Fig. 2 is supported by two parallel brackets 24 resting on the cup 20. Only one bracket is shown in Fig. 2, the other being identical and on the other side of the shaft. I prefer to support the fan by extending bolts (not shown) through appropriate aligned holes in the end plate of the motor and the brackets 24, and by means of nuts 25 securing the motor to the bracket.

It may be observed in Fig. 2 that the brackets 24 are rigidly secured to the cup 20 by means of bolts and nuts or rivets 26 which also aid in supporting an inlet deflector 27.

Three brackets 28 arranged 120 degrees apart are rigidly secured to the cup 20 by bolts and nuts or rivets 30. The deflector 27 also is supported by the last named securing means. The brackets 28 support an air deflector 31, an air deflector 32, and a combination air deflector and shield member 33. Slots are cut in the deflectors 31 and 32 to provide bent over lugs 34 arranged to cooperate with the brackets 28. Holes are provided in these lugs and in the brackets so that bolts and nuts or rivets 35 may be inserted therethrough rigidly to secure the parts. The ends of the brackets 28 are turned to provide a means for securing deflector 33 by means of bolts and nuts or rivets 36.

At its upper end, the deflector and shield member 33 has fastened thereto three brackets 37 arranged 120 degrees apart, the ends of which have turned up portions 38 supporting a cup 40. The cup 40 has an opening in the center of its base (not shown) to which a lamp socket 41 is secured within the cup 40 in a well-known manner, e. g. by an externally threaded tube of the socket assembly extending through the opening and a nut on the outside of the cup screwed thereon with the cup base clamped between the socket assembly and the nut.

The brackets 37 also support an air deflector 42, and three upstanding brackets 43 are secured to brackets 37 to support a combination air deflector and light reflector 44. The manner by which the brackets 37 and 43, and the deflectors 33, 42, and 44, and the cup 40 are fastened may follow the principles described for the lower elements and it is not deemed necessary to burden this description with such details which are obviously subject to a wide choice of equivalents. The number of brackets and their arrangement is largely a matter of choice but it is important that whatever the construction the bracket supporting members be hidden from normal view. By normal view I mean generally, the visible picture of the combination to a person observing the unit during customary positions and actions in the premises in which the unit is located.

The deflector and reflector 44 has a central opening 45 serving two purposes, one of which is

to permit a lamp bulb 46 to be screwed into the socket 41 and the other of which will be subsequently described.

The combination deflector and shield 33 is concave outward as shown and is slightly tapered upward inasmuch as I have found this form to yield an efficient and silent air stream. The ends of the propeller blades are substantially opposite the smallest diameter of the deflector 33 which at this diameter just clears the outermost path of the blades. By this construction I prevent air eddy currents which not only are a source of noise but also decrease the over-all efficiency of the air moving unit.

In my preferred construction the deflectors 27, 31, and 32 terminate above the bottom of the deflector 33, and lie substantially in a plane which is in proximity to the propeller. The deflectors 27, 31 and 32 are equally spaced and have gentle concave outward curves of decreasing radius downwards. I prefer to terminate the lower end of the deflector 32 somewhat beyond the deflector 33 while the deflectors 31 and 27 are of increasing height but decreasing diameter respectively. The upper deflector 42 terminates below the top of the deflector 33 and is of gentle curvature throughout with concavity outward, as shown, and is spaced from the deflector 33 a somewhat greater distance than that between deflectors 32 and 33. It may be seen, however, that the height of the deflector is such as to give a symmetry of appearance. The deflectors as a whole have a harmony of design of flaring elements and hide from normal view the propeller and other internal structures which would, if visible, mar the appearance of the unit.

The element 44 is shaped to provide a concentration, or dispersion, or both, of the light from the spheroidal part of the bulb 46. In general the curvature of the element 44 as a light reflector is sufficiently gentle to provide a smooth air flow path on its under side whereby the element 44 also acts as an air deflector. The cup 40 and the combination deflector and reflector 44 are positioned so as to be substantially hidden from view by the deflector 42, and their positions relative to the propeller may be made to depend on the direction it is desired to have the outflowing air go.

The neck 41 of the bulb is below the reflector 44 which with modern frosted lamps may be deemed a secondary source of illumination. Light coming from the neck illuminates directly or by reflection, or both, the outside surfaces of the deflectors and by painting these surfaces in soft pastel shades I obtain a very pleasing light effect. Obviously the outside surfaces of the deflectors if they be metal may be polished or otherwise treated to obtain any lighting effect desired. The inner surfaces of the lower deflectors 31 and 32, and the shield deflector 33 may be polished or otherwise treated as by painting white to provide better reflecting surfaces for more efficient utilization of the light. Moreover, by increasing the size of the opening 45 I can increase the amount of light from the bulb which ultimately falls upon the outside surfaces of the deflectors. I prefer to choose the speed of the fan motor and the number of blades in the propeller such that the product of the two will provide a flicker frequency great enough to prevent, due to human persistency of vision, any discernible flicker of the light. However, for display purposes the product may purposely be chosen to create a visible flicker.

Power may be supplied to the unit from a two wire lamp cord 50 which extends through one of the iron pipes aforementioned, and terminates in one of the members of a household detachable plug 51. The other member of the plug has a two wire cord connecting to a two circuit canopy switch 52 mounted on the base 20, which is of the common variety having knobs independently rotatable about a common axis.

The knob 53 may be part of a one way switch for controlling the supply of power to the motor while the knob 54 may be part of a multi-way switch for controlling the different circuits to the bulb 46 which in my embodiment is of the two filament type connected to give three different light intensities. Obviously, the number of ways controlled by the knobs will depend on the type of bulb used, and on the motor control. Thus, if a multi-speed motor is desired, the knob 53 can control more than one circuit. Of course, if one desires, structurally independent switches may be employed to control the lamp and the motor.

The leads from the switch to the motor are hidden from view in the cup 20, and the cable lead 55 from the switch to the lamp is conducted along one of the brackets 28, up the inside of the shield deflector 33, and along one of the brackets 37 to the lamp socket. The cable may be secured in position by one or two turns of wire or cord 56 which winds around the cable and bracket as shown. As many such fastening means may be employed as is deemed necessary adequately to hold the cable in place. This cable, it may be seen, is also hidden from view and is out of the path of the four blades of the air propeller.

In assembling the head on the pedestal the male and female detachable plug members are cooperatively engaged and the entire plug may be set into the cup 17 which is provided for that purpose. When the tapering housing 13 and the cup 20 are properly mated, the switch 52 extends through a hole 57 in the annular base 14. The taper fit between the housing 13 and cup 20 is designed so that the switch 52 protrudes a sufficient distance below the housing 13 to be operable. This fit, when secure, also provides space between the bottom of the cup 20 and the base 14 so that the bottom of the cup 20 does not rest upon the nuts 18 or the lamp cord 50.

A central aperture 58 is provided in the base of the cup 20 as shown in Fig. 4, and is of a diameter sufficient to permit the plug 51 to pass therethrough. The bottom of the motor 21 is spaced from the bottom of the cup 20 so that if desired the plug 51 may be inserted upward through the aperture 58 and disposed in the cup 20 rather than in the cup 17. This adapts the head unit to a pedestal having a single stem rod which would naturally be secured in the center of the cup 13.

In Fig. 3 is shown a modification of the bracket 37. In this figure the bracket 37' is placed edge-wise so as to minimize its resistance to the air flow. The ends are bent sideways as shown and the lug cuts in the deflector 42' are such as to provide a lug cooperating with the bracket 37'. The bracket 43' fastens directly on the bracket 37' without a bend but a twist is made at its upper end to obtain a secure fastening support for the reflector 44.

My combination unit is easily adapted to some degree of air conditioning. Thus, a removable humidifier 60 may rest within and on the deflector 42. The humidifier has its walls shaped so that when in position the air flow between it and

5 the deflector 44 is not obstructed to any objectionable degree. The humidifier has a wick 61 and a capped covered port 62 through which the supply of water in the humidifier may be replenished. If desired, a disinfectant (not shown) may be hung within and on one of the deflectors so as not to be visible. Or a heating unit (not shown) may be incorporated in the spaces between deflectors 27, 31, and 32, for example, in a manner as to be hidden from view, as is obvious to a skilled person.

In operation of the fan, the intake air is guided to the propeller in gentle flow paths by the deflectors 27, 31 and 32, and the bottom portion of deflector 33 while the outlet air is similarly guided by the upper portion of the deflector 33 and deflectors 42 and 44. When placed in a room a marked circulation of air is obtained as is apparent since air is drawn from below and exhausted above the unit resulting in somewhat circular air currents in the room. Manifestly the configuration and number of the deflectors may be varied to vary the paths of the air currents by making the deflector 42 and the upper portion of deflector 33 of greater or lesser concavity, and the same is equally true of the lower portion of the deflector 33 and deflectors 27, 31 and 32. The curvature of the deflectors will be determined largely by the type and use of the combination unit inasmuch as in a table lamp structure or the like for example, it may be desired to discharge the air vertically in some instances, or more nearly horizontal in other instances to blow air directly upon persons seated about the table on which the unit rests. However, I prefer to discharge the air in a unit resting on the floor generally upwards so that circulation of air is obtained without drafts.

It may be observed that I provide apertures 63 in the cup 20 through which an amount of air may be drawn that will effectively cool the motor 21. Moreover, the lamp socket holder cup 40 is positioned directly above the center of the propeller, at which place there is substantially no air flow thereby providing very little, if any, interference to air flow and resulting in quiet operation. I may also provide beads such as 64 at the outer peripheries of the deflectors for ornamental purposes.

A distinct advantage I obtain with my unit is the effective circulation and therefore intermixing of air within a room. In this manner a uniform temperature is obtained. By having the lower deflectors nested as shown and of gradually decreasing diameter, I prevent air exhausted from the upper part of the unit from being immediately drawn back into the unit, which I had found to be a serious fault and which decreased the effectiveness of the unit considerably.

In Fig. 4 I show another embodiment for a head unit capable of being used upon a pedestal. The construction of the inlet deflectors is along the lines of that of Fig. 2 but the outlet portion has three spaced deflectors 65, 66 and 67 the upper of which also acts as a reflector for a light bulb 46. Apertures 68 may be formed in these deflectors if desired to aid in the indirect lighting of the outside surfaces of the deflectors but I have found that some light is reflected from the blades of the propeller onto these surfaces, which may be sufficient for some purposes. Additional light effects can be obtained by covering the apertures with different colored translucent members.

The outlet deflectors are maintained in posi-

tion by long bolts 10 having spacers 11, 12 and 13 properly spacing and holding the deflectors. For greater rigidity brackets such as 14 secured to and between deflectors may be utilized. As many bolts and brackets may be employed as are deemed essential.

My invention is not limited to units resting upon a floor, and in Fig. 5, I show the general principles of my invention applied to a fixture of the chandelier type, that is, one suspended overhead from a ceiling. Such a unit is usually wider than the floor type unit and I have therefore shown four inlet deflectors. The number of inlet deflectors will depend largely on the desired appearance of the unit but their disposition and configuration conform to the construction principles described for the embodiment of Figs. 1 and 2. In a unit of the chandelier type a wall switch usually controls the power supply and I have added a pull chain switch 15 for controlling the motor. In this unit for the sake of simplicity the bulb is of single intensity and the motor a single speed motor. However, multi-intensity bulbs and multi-speed motors may be employed with appropriate wiring and switches, as is obvious to the ordinary electrician. It may be observed that the top deflector has a bowl portion 17 and this deflector conforms in shape to the usual fixture for reflecting and dispersing the light. If it be desired to obtain lighting effects upon the outside surfaces of the deflector an opal glass unit or other translucent or transparent member 18 may be inserted in an aperture of the deflector 16 cut out for the purpose.

In Fig. 6 I show another and preferred structure by which the different parts of my unit can be supported. Instead of separate brackets such as 24 and 28 of Fig. 2, I provide a cast or otherwise formed spider 80 comprising a ring 81 with integral arms 82. As many arms may be provided as desired but I have found that three arms spaced 120 degrees apart result in a satisfactory support. The arms 80 each have end lugs 83 and intermediate lugs 84 integral therewith. The ends of deflectors such as 21, 31, 32 and 33 abut these lugs, and bolts or rivets may be inserted through cooperating holes in the deflectors and lugs by means of which the parts may be secured to the spider. The angles of the lugs and their number will, of course, correspond to the deflectors fastened thereto.

The ring 81 also has protuberances or ears 85 through which the bolts aforesaid on the motor 21 extend so that the motor may be suspended within the ring 81. After the assembly of the motor to the ring, the cup 20' having switch 52 mounted thereon may be secured to the ring through the medium of bolts passing through aligned holes 86 and 87 after the proper wire connections have been made. I also may cast or form a supporting structure equivalent to the cup 40 and the brackets 37 in a similar manner, as is at once obvious.

It is clear that many other embodiments may be constructed utilizing the teachings of my invention, as for example, while I have shown the deflectors as tubular-like members of surfaces of revolution yielding a circular cross section, the cross section may be formed to any desired shape suitable to the purposes of my invention, and the deflectors themselves need not be continuous at all cross sections. I therefore desire that the following claims and terms used therein be given a broad interpretation limited only by the prior art.

I claim:

1. A fan for a room or similar enclosure, comprising a rotatable propeller for propelling the air-flow axially thereof; means for rotating said propeller; a tubular shield and air deflector member about said propeller, having an intermediate portion in close proximity to said propeller; tubular, flared, concave outward, air inlet and air outlet deflectors having one of their ends within, and spaced from, said member, but in proximity to said propeller, and having their other ends extending beyond said member, said deflectors being flared from said propeller for quietly guiding the air-flow in gentle curved arcs directly to and from said propeller, which arcs are substantially tangent, at said propeller, to a line parallel to said axial direction for the air-flow.

2. A fan for a room or similar enclosure, comprising a rotatable propeller for propelling air axially thereof; means for rotating said propeller; a tubular shield and air deflector member about said propeller, having an intermediate portion in close proximity to said propeller; concentric, tubular, flared air inlet deflectors, said deflectors being concave outward, the outer of said deflectors having one end within said member and its other end projecting beyond an edge of said member but of substantially the same periphery as the said edge, the last said deflector being spaced from said member, ends of the relatively inner of said deflectors terminating relatively further from said propeller, but of shorter periphery toward the axis of said propeller; a tubular, flared air outlet deflector terminating within said deflector member and projecting beyond the other edge of said member; the flares of said deflectors being such that the air is guided in gentle curved arcs directly to and from said propeller, which curved arcs are substantially tangent to a line parallel to the axis of said propeller, whereby discharging air is not immediately drawn back into the fan along the outside surface of said member.

3. The structure of claim 1 including a substantially frusto-conical air outlet deflector axially within, and spaced from, the first said outlet deflector, and having an undulating outer surface for guiding the air-flow, the said frusto-conical deflector being inverted and over said propeller.

4. The structure of claim 1 including a substantially frusto-conical air outlet deflector axially within, and spaced from, the first said outlet deflector, and having an undulating outer surface for guiding the air-flow, the said frusto-conical deflector being inverted and over said propeller; and lighting means within said frusto-conical deflector which thereby also acts as a reflector therefor.

5. The structure of claim 1 in which said member is concave outward with its shortest periphery intermediate its ends and in proximity to said propeller, the axial length of said member being only slightly greater than that of said propeller.

6. A fan for a room or similar enclosure, comprising a rotatable propeller for propelling air axially thereof; a motor for rotating said propeller; a tubular shield and air deflector member about said propeller, said member being concave outward with its shortest periphery in proximity to said propeller; concentric, nested, inlet air deflectors of relatively gradual increasing length and decreasing radii inward, the inner of said deflectors outwardly encasing said motor; nested

air outlet deflectors; said deflectors being slightly flared and cooperating with said member and each other to guide the air flow to and from said propeller in gently curved arcs which are concave outward and substantially tangent, substantially at said propeller, to lines substantially parallel to the axis of rotation of said propeller.

7. A combination lamp and fan unit comprising a fan having a propeller for propelling air substantially vertically upward, spaced air inlet deflectors and spaced air outlet deflectors on respective sides of said propeller, said deflectors being substantially tubular and flared outwardly and away from said propeller for quietly guiding the air flow to and from said propeller in gently curved vertical concave-outward arcs, indirect illuminating means for projecting light generally upwardly, and means for mounting said indirect illuminating means within said outlet deflectors, said indirect illuminating means and deflectors being constructed and arranged so that light from said illuminating means falls on outside surfaces of certain of said inlet deflectors.

8. A combination lamp and fan unit comprising a fan having a motor and a rotatable propeller driven thereby, said propeller being adapted to move air substantially vertically, a substantially tubular member about said propeller and projecting beyond said propeller on both sides thereof, a tubular air inlet deflector having an end terminating within, and spaced from, said member and extending below said member, a tubular air outlet deflector having an end terminating within, and spaced from, said member and extending above said member, said deflectors and member being slightly flared outward and away from said propeller for quietly guiding the air flow, said inlet deflector substantially encompassing said motor, an indirect illuminating means within said outlet deflector and immediately above the center of said propeller, whereby it does not seriously interfere with the air flow.

9. A combination lamp and fan unit comprising a fan comprising a motor and a rotatable propeller for moving air axially of said motor, a tubular member about said propeller, a plurality of spaced, concave outward, nested air inlet deflectors with the relatively inner of said deflectors terminating below the relatively outer of said deflectors, said deflectors encompassing said motor, an illuminating means, a tubular, flared, air outlet deflector having one end near said propeller terminating within, and spaced from, said member and extending above it, a second air outlet deflector having an end within, and spaced from, the first said outlet deflector, said second deflector being above the center of said propeller and constructed and arranged as a reflector for said illuminating means.

10. The unit of claim 9 characterized by said second air outlet deflector having an open bottom, and said illuminating means comprising a light bulb and means for supporting said bulb with a portion thereof within said second air outlet deflector and a portion below said second air outlet deflector whereby outside surfaces of certain of said deflectors may be illuminated.

11. As an article of manufacture, a vertically extending pedestal having a base support at one end and an air-circulating head at the other end, said head comprising a fan comprising a motor and a rotatable propeller for propelling

air substantially vertically, a substantially tubular shield and air deflector member about said propeller, a substantially tubular air inlet deflector having one end terminating within and spaced from said member and the other end below said member, a substantially tubular air outlet deflector having one end terminating within and spaced from said member and the other end above said member, the first said end of said air inlet deflector and the first said end of said air outlet deflector being in proximity to said propeller, said member and said deflectors being flared for quietly guiding the air flow to and from said propeller in gently curved vertical concave-outward arcs, the said deflectors having a maximum size transverse to the axis of said propeller approximately the same, or less than, that of said member.

12. As an article of manufacture, an air circulating device for use in an enclosure, comprising a vertically extending pedestal having a base support at one end and an air-circulating head at the other end, said head comprising a fan comprising a motor and a rotatable propeller for propelling air in the general direction of its axis of rotation, a substantially tubular member about and close to said propeller, spaced nested lower air deflectors having ends within said member terminating in proximity to said propeller for guiding inflowing air directly to said propeller, an upper air deflector having an end terminating in proximity to said propeller for guiding outflowing air directly from said propeller, said deflectors being flared for guiding the air flow to and from said propeller in gently curved concave-outward arcs.

13. As an article of manufacture, an air circulating device for use in an enclosure, comprising a vertically extending pedestal having a base support at one end and an air-circulating head at the other end, said head comprising a fan comprising a motor and a rotatable propeller for propelling air in the general direction of its axis of rotation, a substantially tubular member about and close to said propeller, spaced nested lower air deflectors having ends within said member terminating in proximity to said propeller for guiding inflowing air directly to said propeller, an upper air deflector having an end terminating in proximity to said propeller for guiding outflowing air directly from said propeller, said deflectors being flared for guiding the air flow to and from said propeller in gently curved concave-outward arcs, said inlet deflectors terminating one below the other with the lower end of the relatively inner of said inlet deflectors of smaller periphery than the relatively outer of said inlet deflectors.

14. A combination lamp and fan unit adapted for suspension in a room and comprising a fan having a motor and propeller for propelling air in a single direction, a tubular shield and deflector member about said propeller, flared spaced nested air inlet deflectors for guiding inflowing air directly to said propeller, flared spaced air outlet deflectors for guiding outflowing air directly from said propeller, a light bulb, and means for mounting said light bulb within the inner of said air outlet deflectors, the last said deflector being constructed to serve as a reflector for light rays from said light bulb.

ALEXANDER E. BLUMENTHAL.
